UNITED STATES PATENT OFFICE.

NAPOLEON DU BRUL, OF CINCINNATI, OHIO.

DESIGN FOR A PRESS-FRAME.

SPECIFICATION forming part of Design No. 32,511, dated April 10, 1900.

Application filed March 7, 1900. Serial No. 7,733. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for a Press-Frame, of which the following is a specification.

My new design is illustrated in the accompanying drawings, which represent a press-frame embodying the same, and in which—

Figure 1 is a side elevation; Fig. 2, a rear view, and Fig. 3 a plan.

As shown in the said drawings, the leading or material features of my said design are the base, an arm projecting upwardly from said base, and a head supported by the upper end of the arm, having its greater transverse di-

mission in the plane of said arm and with approximately-vertical front face and a rear face substantially vertical for a portion of its height and then sloping forward to a curving top.

Having thus described my said invention, I declare that what I claim as new, and desire to secure by Letters Patent, is—

The design for a press-frame, substantially as herein shown and described.

Signed at Cincinnati, Ohio, this 8th day of January, 1900.

NAPOLEON DU BRUL.
